UNITED STATES PATENT OFFICE.

JOHN SPEICH, OF SACRAMENTO, CALIFORNIA.

TWIN GRAFTING-TOOL.

1,282,132.

Specification of Letters Patent. Patented Oct. 22, 1918.

Application filed September 17, 1917. Serial No. 191,870.

To all whom it may concern:

Be it known that I, JOHN SPEICH, a citizen of the United States, residing at Sacramento, in the county of Sacramento, State 5 of California, have invented certain new and useful Improvements in Twin Grafting-Tools; and I do declare the following to be a full, clear, and exact description of the same, reference being had to the accompanying 10 drawings, and to the characters of reference marked thereon, which form a part of this application.

This invention relates to improvements in tools used for grafting. The object of the 15 invention is to provide a tool which will perform the complete operation of forming the hole for receiving the graft. To this end I aim to have one portion of the tool to be driven into the tree to form a V shaped incision and then the other portion of the 20 tool is driven in to cut out the third side, making a clean three sided cut in the tree with the use of the single tool.

A further object of the invention is to 25 produce a simple and inexpensive device and yet one which will be exceedingly effective for the purposes for which it is designed.

These objects I accomplish by means of 30 such structure and relative arrangement of parts as will fully appear by a perusal of the following specification and claims.

In the drawings similar characters of reference indicate corresponding parts in the several views.

35 Figure 1 is a side elevation of the complete tool partly broken out and in section.

Fig. 2 is a sectional view of the tool taken on a line $\alpha-\alpha$ of Fig. 1.

Fig. 3 is a top line view of the cutters.

40 Referring now more particularly to the characters of reference on the drawings, I first provide a V shaped cutter 1, having a rearwardly projecting shank 2 terminating in a head 3. Pivoted on the shank 45 2 is a guide 4 provided with a strap 5 extending around the shank 2 and through which is threaded a thumb screw 6. This thumb screw 6 engages the shank 2 for the purpose of adjusting the relative position 50 of the guide 4 on such shank. The guide 4 is provided with a pair of slotted members 4^a and 4^b. Slidably through these slotted members is the shank 7 of the other cutter blade 8. This cutter blade is flat and 55 pointed and moves between the top edges of

the V shaped cutter blade 1 which also terminates in a sharp point. The shape of the blade 8 is such that when it is moved between the sides of the blade 1 it completely fills the space between such sides, so that the 60 outer edges of the blade 8 come into engagement with the edges of the blade 1.

The blade 8 is normally held retracted from engagement with the blade 1 by means of a spring 9 mounted around the shank 7 65 and interposed between the member 4^a and a pin 10 on said shank 7 whereby the pressure of said spring 9 holds the shank in that position which will maintain the blade 8 from engagement with the blade 1. When it is desired to use the tool, the blade or cutter 1 is 70 driven into the tree with a hammer, or other instrument, used against the head 3. The shank 7 is then likewise driven to force the blade 8 into the tree, and when this is done 75 a three cornered piece is removed from the tree, leaving a similar shaped hole therein into which the grafting splice may be inserted.

The adjusting thumb screw 6 is used to 80 position the edges of the blade 8 with respect to the blade 1 so that they will come together when the cut is being made so as to make a good clean three-cornered hole for the graft. If this adjustment is not provided, then if the blades become slightly 85 worn or sprung, the piece cut from the tree might have a thin adhering portion which might have to be torn away. This would leave a ragged edge which is undesirable. 90 By having such adjustment screw 6, however, the two blades may be kept adjusted so as to make a clean cut at all times.

The proper position of the pivoted guide 4 is maintained by means of a strong spring 95 11 interposed between the shank 2 and such guide 4. This spring 11 also maintains the blade 8 in its proper position relative to the blade 1. When, however, the cut has been made and the piece of wood is between the 100 blades, the member 7 is pressed toward the member 2 against the pressure of this spring 11. This lifts the blade 8 clear of the blade 1 and permits the piece or core of wood to be readily removed.

105 From the foregoing description it will be readily seen that I have produced such a device as substantially fulfills the object of the invention as set forth herein.

While this specification sets forth in detail 110

the present and preferred construction of the device, still in practice such deviations from such detail may be resorted to as do not form a departure from the spirit of the 5 invention, as defined by the appended claims.

Having thus described my invention what I claim as new and useful and desire to secure by Letters Patent is:

- 10 1. A grafting tool comprising two coöperative blades, each having a driving shank, a guide pivoted on one shank, the other shank being slidable in the guide, and means for adjusting the position of the guide on the shank, such means comprising a strap on the guide surrounding the shank and a thumb screw threaded through the strap and engaging the shank.
- 15 2. A double-edged grafting tool including a fixed blade and a blade movable in the plane in which the edges of the fixed blade lie to cut a grafting core which will be enclosed between the blades, the blades being pivotally mounted for relative lateral movement whereby they may be spread apart to allow the removal of the core.
- 20 3. A grafting tool comprising two coöperative blades, each having a driving shank, a guide for one shank pivoted on the other shank, whereby the two blades may be

35 moved away from each other to allow the core to be removed from between the blades, and a spring interposed between the shanks to hold the blades in normal cutting position.

4. A grafting tool comprising two coöperative blades, each having a driving shank, a guide for one shank pivoted on the other shank, and means for adjusting the position of the guide relative to the shank 40 on which it is pivoted to allow the relative position of the cutting edges of the blades to be adjusted at will.

5. A grafting tool including a V-shaped blade, the edges thereof tapering to a point 45 at their outer end, a blade movable in the plane in which the cutting edges of the V-shaped blade lie and adapted to form the third side of the V-shaped blade when the core is cut whereby the cut core will be enclosed between the blades, the blades being pivotally mounted for relative lateral movement whereby they may be spread apart to allow the removal of the core.

50 In testimony whereof I affix my signature in the presence of two witnesses.

JOHN SPEICH.
